(57) **CLAIM**

What is claimed is the ornamental design for a wireless charging station, as shown and described.

DESCRIPTION

FIG. 1 is a front upper perspective view showing the wireless charging station of Applicant's new design.

FIG. 2 is a rear upper perspective view thereof.

FIG. 3 is a rear lower perspective view thereof.

FIG. 4 is a right side elevation view thereof.

FIG. 5 is a left side elevation view thereof.

FIG. 6 is a front elevation view thereof.

FIG. 7 is a rear elevation view thereof.

FIG. 8 is a top plan view thereof.

FIG. 9 is a bottom plan view thereof; and,

FIG. 10 is a front upper perspective view of the wireless charging station of FIG. 1, shown in a condition for use with a power cable.

The broken lines on the wireless charging station depict portions of the wireless charging station that form no part of the claimed design. The broken lines showing a power cable in FIG. 10 depict environmental subject matter that forms no part of the claimed design.

1 Claim, 9 Drawing Sheets
